UNITED STATES PATENT OFFICE.

HILMAR ANDRESEN, OF CHICAGO, ILLINOIS.

BRIDGE.

1,337,187.

Specification of Letters Patent. Patented Apr. 20, 1920.

Application filed June 23, 1919. Serial No. 805,975.

To all whom it may concern:

Be it known that I, HILMAR ANDRESEN, a citizen of the United States, and a resident of Chicago, in the county of Cook and State 5 of Illinois, have invented certain new and useful Improvements in Bridges; and I do hereby declare that the following is a full, clear, and exact description thereof, reference being had to the accompanying drawings, and to the letters of reference marked 10 thereon, which form a part of this specification.

This invention relates to improvements in locking devices for trunnion bascule bridges 15 or structures of a similar type. One of the objects of the invention is to provide a locking device that is independent of the main or driving machinery, and which device shall firmly hold the swinging portion of 20 the bridge in such manner as to be immovable in any position of the bridge, and at the same time permit the release of the locking structure at the proper time, to permit the swinging of the bridge leaf back to its 25 normal position.

My invention further has for one of its objects the location upon the swinging or movable leaf of the bridge structure of brake operated mechanism of the compressed air 30 type and of locating on the fixed or non-swinging part of the bridge, suitable means for originating and supplying compressed air to the brake operating mechanism.

Another object of my invention is to provide 35 a brake gripping mechanism located upon the swinging portion or leaf of the bridge in such position as to operatively grasp a brake rail fixed immovably in the abutment which constitutes a part of the bridge structure as a whole, said mechanism for actuating said locking brake being located upon the movable part of the bridge, while the means for controlling said brake operating mechanism is located upon the 40 shore or the bridge operator's house.

Another object of my invention is to provide 45 a main storage or supply tank for the compressed air upon the non-movable part of the bridge structure, and an auxiliary air supply tank on the movable part or leaf of the structure, the two tanks being suitably connected, and automatic means for supplying compressed air from the stationary main supply tank to the movable auxiliary supply tank when the pressure in the latter is

momentarily reduced by the operation of the brake operating mechanism.

A still further object of the invention is to connect the source of air supply from the stationary tank to the brake operated mechanism through the hollow trunnions of the movable part or leaf of the bridge structure, so that the movement of the bridge will not interfere with the source of air supply. 60

These and other objects of my invention 65 will be manifest as I proceed with my specification.

In the drawings:

Figure 1 is a skeletonized plan view, partially in section, of a bridge embodying my 70 invention, showing also a portion of the abutments.

Fig. 2 is an enlarged vertical sectional view of the abutment with the swinging end of a bridge leaf in elevation. 75

Fig. 3 is an end elevation of a portion of the bridge structure.

Fig. 4 is an enlarged detail view of the end of the bridge truss shown in Fig. 2, some of the parts being in section. 80

Fig. 5 is a rear elevation enlarged, of the truss member in which the movable clamping block is mounted. 85

Fig. 6 is a vertical, sectional view taken on the line 6-6 of Fig. 4, showing the cylinder operated clamping lever in elevation. 85

Fig. 7 is a horizontal, sectional view of the same on the plane indicated by the dotted line 7-7 in Figs. 4 and 6.

Fig. 8 is a detail cross sectional view of 90 the brake rail and clamping brake shoe shown in Fig. 7, when the brake is released.

Fig. 9 is a side view or elevation of the end of the swinging leaf of the bridge and of the curved brake rail to which my invention has been applied in a modified form. 95

Fig. 10 is an end view of the modification shown in Fig. 9.

Fig. 11 is a sectional view taken upon the line 11-11 of Fig. 10 showing the modified 100 form of clamping brake in elevation.

Referring now to the drawings, Figs. 1 to 8, inclusive, M indicates a portion of the masonry end of the shore abutment to a bridge. T, T, T¹ T¹, and T² T², indicate the 105 trunnions, in pairs, about which two bridge leaves B and B¹, of a bascule lifting bridge structure, are mounted. C indicates an air pump located on shore and suitably connected to a supply tank D similarly located. E, 110

E¹ are auxiliary air supply tanks mounted upon the movable bridge leaves B, B¹, respectively. F, F¹, F² are supply pipes, one branch, F² of which leads through valve G to that trunnion T nearest that part of the abutment on which the pump C and tank D are located. The section F¹ of the supply pipe leads across the width of the bridge to the opposite ends of the abutment, and 10 through the branch pipe F³, and valve G¹ leads to the farthermost pair of trunnions designated as T², T².

The trunnions T¹ T¹, and T² T² are hollow, so that compressed air is admitted 15 therethrough when the valves G and G¹ are open. In order to supply compressed air through the trunnions to the auxiliary air supply tanks, E, E¹, a pipe line H leads from the trunnions T¹ T¹, and is connected 20 with the auxiliary tanks E on the leaf B, and a similar branch pipe H¹ connects the trunnion T² T² with the tanks E¹ on the leaf B¹. By this arrangement, I provide, 25 apparatus for supplying compressed air that is located upon the stationary abutment to the series of auxiliary tanks E which are located upon and movable with the moving bridge, suitable swivel joints S, S¹ being provided in the branches F² and F³.

30 I do not illustrate the details of mechanism whereby the said branch pipes leading through said trunnions are properly packed to permit the swinging movement of the bridge and at the same time to permit the 35 compressed air to pass through said trunnions without leaking, as any suitable swivel joint on the market may be employed, since the swivel joint is but an incidental feature of the structure.

40 Upon the shore end of the moving leaves B, B¹ of the bridge, I provide suitable brakes adapted to engage a brake rail stationarily mounted on the shore abutment. In Figs. 1 to 8 inclusive, the brake rail is 45 designated at I and is shown (more particularly Figs. 2 to 4) as a curved rail suitably anchored inside of the masonry end of the abutment, while the brake, as a whole, is designated at J. Near each auxiliary tank

50 E, E¹, an air operated cylinder K is located on the leaves B, B¹, the piston K² of each cylinder K being in operative connection with a brake J. When the bridge is turned on its trunnions by suitable operating mechanism, (not shown) the shore end of the leaves B, B¹ will swing substantially in the arc of a circle indicated by the curvature of the brake rails I. The several brakes J, being in juxtaposition to said brake rails, will

55 slide easily thereover. When the bridge is in the desired position and it is desirable to lock the bridge to the shore abutment through the brake and brake rails, the proper valves are opened and air pressure admitted from the auxiliary tanks E into

the adjacent cylinders K, said valves being magnetically operated from the bridge house. Thus the several cylinder pistons are forced outwardly to simultaneously operate the several brakes J to clamp upon 70 the brake rails I. Immediately the pressure in the auxiliary tanks E, E¹ is thus lowered, automatic valve connections in the pipe lines supply the deficiency from the main tank D. Automatically operated 75 valves between the main tank D and the pump C will simultaneously open to start the pump C into operation. Thus pressure in the tanks D, E, and E¹ will be substantially constant, and maximum pressure will 80 always be available for the operation of the cylinders K. I do not show in my drawings nor think it necessary to describe the details of the automatic valves or connections by which the pump C may be started 85 and stopped and the pressure in the tanks be maintained, nor the stopping and starting valves by which the cylinders K may be operated, as these are incidental to the main purpose of my invention. Any of the well 90 known types of valves may be used, and will be readily understood by the engineer or mechanic.

Referring now to the brake structure proper, the bridge trusses are designated 1, 95 2, 3, and 4. It will be noticed that the trusses 1 and 2 indicate half of the bridge or the bridge leaf B¹, while the trusses 3 and 4 indicate the other individual half or bridge leaf B. These two leaves B and B¹ 100 may be operated separately or as a unit according to the particular design of the bridge. Each truss 1, 2, 3 and 4, however, is provided with a pair of trunnions as shown. Upon the bottom side of each of the trusses 1 and 2, 3 and 4, is located a pressure cylinder K each with its auxiliary tank and all suitably connected by the air supply pipe lines previously described.

Referring now more particularly to Figs. 110 2, 4, 6 and 7 it will be seen that each cylinder is provided with a piston rod K² which is pivotally connected with an operating lever 6. The lever 6 is pivoted at 7 to the upper end of the brake structure and is provided with a fulcrum pin 8 intermediate its ends. The brake J includes a brake head 9 115 slideable and longitudinally movable within a guide frame or bumper casting 10, secured to and a part of the bridge structure. A link arm 11, pivotally secured at one end by the bolt 12 to the brake head 9, is connected to the lever 6 at its other end by means of the fulcrum 8. The brake shoe or rail gripping end of the brake J is preferably V shaped 120 and the rail I is preferably A shaped in cross section as clearly shown in Figs. 7 and 8, the complementary surfaces 13—14 thus increasing the friction between them.

In operation, compressed air is supplied 130

to the cylinders K whereupon the piston of each is moved outwardly and through its piston rod actuates the attached lever 6. As the end of the lever 6 swings on its pivot 5 7 toward the brake rail I, it pushes the brake head 9, through the connecting link 11, until the brake shoe J engages the brake rail I, thus firmly locking the bridge leaf in the position in which it happens to be when air 10 pressure is applied to the cylinders K. The arrangement of these parts and their construction and operation is such that tremendous power is exerted and a maximum of braking efficiency is obtained.

15 In the modified form shown in Figs. 9 to 11, inclusive, M indicates the masonry and I¹ the curved brake rail. In this form, the bearing surfaces of the brake are in parallel relation, as shown clearly in Fig. 11. The 20 auxiliary tank E and the cylinder K are mounted upon the end chord of the truss instead of on the bottom chord as in the previously described arrangement.

Within a metal frame 15 and pivotally 25 secured at 16, 16, are a pair of lever arms 17, 17 and upon the lower end of each arm 17 is a brake shoe 18. The two brake shoes 18 are positioned in operative relation upon opposite sides of the brake rail I¹. Their braking surfaces are normally close to the sides 30 of the brake rail I¹, only sufficient space being allowed for clearance in swinging the bridge so that the minimum amount of movement of the levers 17, 17, will cause 35 actual braking contact between the brake shoe 18, 18 and the brake rail I¹.

The arm of each lever 17 is provided near 40 its upper end with a suitable groove or socket 19, in which is engaged a complementally shaped boss or knob 20 upon a lever arm 21. This lever arm 21 is pivoted at one end 22, and at its farther end is connected at 23 with a link 24. The other end of each link 24 is pivotally connected at 25 45 to the piston rod of the cylinder K. When the air pressure is applied to the cylinder K, the piston moves outwardly, forcing the pivots 23 of the links 24 outwardly and spreading apart the upper or long arms of 50 the levers 21. This toggle movement of the links 24 and the levers 21 results in moving bodily outwardly the knobs or projections 20. It also has the effect of pushing the upper or long arm of the levers 17 out- 55 wardly and the short arms of the levers 17 inwardly, thereby clamping the two brake shoes 18, 18, against the sides of the brake bar I¹.

The relation of the toggle composed of the 60 levers 21 and the links 24 with the levers 17 is such that the minimum amount of movement is exerted to produce the maximum amount of brake action, whereby the brake shoes 18 are securely clamped to the brake bars I¹ almost the instant that air pressure

is supplied to the cylinders K, thereby holding the bridge firmly in the desired position.

It will be noted that the masonry part M of the bridge structure supports the source of compressed air, such as the pump 70 C, and the auxiliary tank D, as well as the main supply pipe line, F, F¹ and the branches F² and F³; and also carries the curved or segmental brake rails I, I¹. These parts are fixed and immovable. It will also 75 be noticed that the swinging bridge leaves B, B¹, carry the brakes adapted to engage said brake rails, the auxiliary supply tanks E, E¹, the actuating pressure cylinders K and the connecting mechanism between the 80 said cylinders and the brakes.

It will also be noticed that the trunnions T¹ T¹, and T² T², are hollow and that a portion of the branch supply pipes F² and F³ extends beyond the valves G and G¹ respectively to pass through the trunnions and connect by the branch lines H and H¹ with the auxiliary tanks E and E¹ respectively. Thus the bridge leaves B and B¹, jointly 85 or separately may be moved or swung about their trunnions and their brake operating mechanism will be constantly in operative connection with the source of compressed air from the compressor C and main reservoir or tank D.

95 In Fig. 4 I have illustrated a compressed air connecting pipe 26 leading from the auxiliary supply tank E to the cylinder K, and controlled by an automatic electrically operated valve which I have indicated at 100 N, N. Any suitable form of valve may be used. These valves will be connected by suitable wiring (not shown) along the movable part of the bridge structure to the stationary part of the bridge structure, so as to 105 be operated from the bridge house, by any suitable form of electric switch for turning on and off the current. When it is desired to apply the brake the switch will be turned, the valve N will be operated to open communication between the auxiliary tanks E and the cylinders K. So long as the switch is open the pressure will be maintained and the brakes will firmly grasp the brake rails to lock the movable leaves B and B¹ in the 110 desired position. When it is desired to release the brakes, the switch may be turned off or closed to cut off the pressure through the valve N, and open a suitable exhaust valve or exit port in the cylinders K (not 115 shown) thus permitting the parts to be relaxed and the pistons in the cylinders K to move back to normal position, ready to be again operated when air pressure is supplied.

120 I claim as my invention:

1. In a trunnion bascule bridge, a stationary arched brake rail fixed in the bridge abutment, a movable brake shoe upon the 125 swinging bridge, and means also upon the 130

bridge for operating the brake shoe to clamp said rail.

2. In a trunnion bascule bridge, a stationary arched brake rail, a brake mechanism upon the swinging bridge, and pneumatically operated mechanism upon the bridge for actuating the brake mechanism to engage with and disengage from the brake rail.

10 3. In a trunnion bascule bridge, a stationary arched brake rail, a brake shoe upon the swinging bridge, mechanism also upon the swinging bridge for actuating the brake shoe by compressed air, and means upon the 15 non-swinging part of the bridge structure for supplying compressed air to the actuating means.

4. In a trunnion bascule bridge, an anchored arched brake rail, a brake shoe upon 20 the movable part of the bridge structure, hollow trunnions on the movable part of the bridge structure, mechanism upon the bridge structure for actuating the brake, mechanism on the non-movable part of the 25 bridge structure for supplying compressed air to the brake actuating mechanism through said hollow trunnions.

5. In a trunnion bascule bridge, an anchored arched brake rail, a brake shoe upon 30 the movable part of the bridge structure, hollow trunnions on the movable part of the bridge structure, mechanism upon the bridge structure for actuating the brake, said mechanism including an air pressure 35 cylinder and an auxiliary supply tank.

6. In a trunnion bascule bridge, an arched brake rail located upon a fixed abutment, a brake shoe, means for actuating said brake, said shoe and operating means being located 40 upon the movable or swinging part of the bridge, and means on the non-swinging part of the bridge structure for actuating said brake operating means.

7. In a trunnion bascule bridge, an arched 45 brake rail located upon the fixed or non-movable part of the bridge structure, a brake shoe located on the movable part of the bridge structure, a brake cylinder also located on said movable part, a lever in operative connection with the cylinder and 50 with the brake shoe, and means for supplying compressed air to said cylinder.

8. In a trunnion bascule bridge, an arched brake rail located on the fixed or non-movable part of the bridge structure, a brake 55 shoe located on the movable part of the bridge structure, a brake cylinder also located on said movable part, a lever in operative connection with the cylinder and with the brake shoe, a hollow trunnion and means for supplying compressed air to said cylinder through the hollow trunnions.

9. In a trunnion bascule bridge, a lever pivotally mounted at one end to a movable part of the bridge structure, a cylinder also 65 mounted on said movable part of the bridge structure and operatively connected with said lever, a sliding brake head mounted on said movable bridge structure, a link pivotally connected at one end to said sliding 70 brake head and pivotally connected at its other end to said lever between the ends of the latter, a brake shoe mounted on said sliding head, an arched rail brake anchored on the stationary part of the bridge structure 75 in operative relation to the brake shoe and means for actuating the cylinder.

10. In a trunnion bascule bridge, a lever pivotally mounted at one end to a movable part of the bridge structure, a cylinder also 80 mounted on said movable part of the bridge structure and operatively connected with said lever, a sliding brake head mounted on said movable bridge structure, a link pivotally connected at one end to said sliding 85 brake head and pivotally connected at its other end to said lever between the ends of the latter, a brake shoe mounted on said sliding head, an arched brake rail anchored to the non-movable part of the bridge and 90 having inclined bearing faces, the brake shoe being provided with a recess having complementary bearing surfaces, and means for actuating the cylinder whereby said 95 brake shoe will clamp said fixed rail.

In testimony that I claim the foregoing as my invention I affix my signature in the presence of two witnesses, this 21st day of June, A. D. 1919.

HILMAR ANDRESEN.
